DESIGN FOR A REFRIGERATOR CABINET

Ralph E. Kruck, Springfield, Mass., assignor to
Westinghouse Electric & Manufacturing Com-
pany, a corporation of Pennsylvania

Application July 3, 1936, Serial No. 63,638

Term of patent 7 years

To all whom it may concern:

Be it known that I, Ralph E. Kruck, a citizen
of the United States, residing at Springfield, in
the county of Hampden and State of Massachu-
setts, have invented a new, original, and orna-
mental Design for a Refrigerator Cabinet, of
which the following is a specification, reference
being had to the accompanying drawing, forming
a part thereof.

The single figure is an elevational perspective
view of a refrigerator cabinet showing my design.

What I claim is:

The ornamental design for a refrigerator cabi-
net, substantially as shown.

RALPH E. KRUCK.
